TRAFFIC SIGNAL

Application filed May 14, 1930. Serial No. 452,298.

This invention relates to improvements in vehicle traffic signal apparatus, and one of the principal objects of this invention is to provide reliable and efficient means for displaying a visual signal, at all times illuminated in display position, and operated by the driver of a motor vehicle to indicate the direction in which the driver desires to turn, or to give other information to drivers of other vehicles and to pedestrians, and to provide a signal apparatus which may be used by a traffic officer.

Other objects are to provide mechanism of the character hereinafter set forth, embracing the desired features of simplicity, efficiency and durability.

The invention is directed particularly to an improvement in the operating mechanism for a traffic signal described and claimed in our patent application, filed by us on December 17, 1929, Ser. No. 414,771.

The invention further relates to improvements in actuating mechanism whereby the signal is automatically actuated to stop indicating position, on actuation of the vehicle brake pedal, and may be manually actuated to other indicating positions.

It is to be understood that the structural embodiment of the invention as a whole and its various features as shown is merely illustrative and not restrictive, and that many of the details of construction can be widely varied without departing from the spirit of the invention, and we therefore do not wish to be limited in these particulars or any others except as set forth in the appended claims.

In the drawings: Figure 1 is a sectional elevation of a signal semaphore and housing, the operative parts being shown in their normal inoperative position. Fig. 2 is a sectional elevation of the signal and housing showing the semaphore arm in one of its display positions. Fig. 3 is a side elevation of the signal and housing. Fig. 4 is a fragmentary view of an automobile frame showing the signal housing and a part of the operative mechanism thereon. Fig. 5 is a fragmentary view showing a part of the automobile flooring and brake pedal, and a part of the operative mechanism. Fig. 6 is a detail and plan

of the mechanism shown in Fig. 5. Fig. 7 is a front elevation of the control box showing the lever for manual actuation of the signal. Fig. 8 is a front elevation of the control box with cover removed. Fig. 9 is a sectional elevation of the control box. Fig. 10 is a detail view of the actuating cam. Fig. 11 is a side elevation of the actuating cam. Fig. 12 is a front elevation of the lever which is actuated by the brake pedal. Fig. 13 is a side view of the lever which is actuated by the brake pedal. Fig. 14 is a front elevation of a modified form of control box. Fig. 15 is a front elevation of the modified form of control box with cover removed. Fig. 16 is a sectional elevation of the modified form. Fig. 17 is a detail view of the actuating lever. Fig. 18 is a front and detail view of the actuating lever. Fig. 19 is a front view of the modified actuating cam. Fig. 20 is a detail view of the signal actuating shaft. Fig. 21 is a detail plan view of the actuating spring.

Referring in detail to the drawings, our improved signal apparatus consists of a housing 22, having an opening 23, and a hinged cover 24, at the top, normally retained in closed position by spring 25. The housing is supported by bracket 26, mounted on automobile frame member 27 and adjacent to windshield 28. Control box 29 is adapted to be secured to frame member 27, and a metal conduit 30 extends from control box 29 to housing 22. Control box 29 has a cover 31 bearing signal characters "S", "L", and "R". Member 29 has integral stop pins 32 and 33, a pivot shaft 34, and lug 35. Cover 31 is secured to box 29 by screws 36. Shaft 37 is journalled in housing 29, and has fixed thereto a flexible shaft 38 extending through conduit 30 and into the signal housing 22, and which is fixed to a square section signal shaft 39, bearing semaphore 40. Shaft 37 has an actuating handle 41 and a pointer 42, whereby the semaphore may be actuated to any signal position as determined by the characters "S", "L", and "R", and has an actuating cam 43, thereon, and provided with a lug 44. A pawl 45 is operatively mounted on pivot shaft 34, and is actuated to en-

gage with cam 43, by spring 46, interposed between the cam and lug 35. Pawl 45 engages with relatively broad notches 47, which determines neutral and non-display position; 48, which determines display position for left turn signal; and 49 which determines display position for right turn signal. For the stop signal position, pawl 45 will engage with cam section 50; the pawl being spring-
10 actuated, will, when released, automatically actuate the cam to neutral position. Lever 51, independently operable on shaft 37, engages with 44 to actuate cam 43 and shaft 37, and is limited in movement by stop pins
15 32 and 33.

Signal shaft 37 may be manually actuated by handle 41 to any signal position. To actuate shaft 37 on movement of pedal 52, we provide operating mechanism, consisting of link 53 operatively connected to lever 51, and to arm 54 of rock shaft 55, journalled in bracket 56 secured to steering column 57 of an automobile. Rock-shaft 55 has collar 58 clamped thereon by screw 59, and spring 60 disposed on the rock-shaft and connected to bracket 56 and screw 59, and serving to actuate lever 51 to neutral position. Rock-shaft 55 has arm 61 in which is journalled a rotatable stud 62. Link member 63 is fixed to stud 62, and terminates in angular stop member 64, adapted to engage with automobile flooring 65, thereby limiting turning movement of rock-shaft 55. Link member 63 has a collar 66 fixed thereto by screw 67, and has a slidble sleeve 68 mounted thereon, and provided with hook 69. Spring 70 is connected to hook 69 and screw 67. Lever 71 is pivotally connected relative to member 72 on flooring 65, and is pivotally connected relative to slidble sleeve 68, and is interposed in the path of pedal 52.

On initial movement of pedal 52, lever 71 will be actuated, thereby actuating link 63, collar 66, sleeve 68 and spring 70, as a single unit until sufficient movement of rock shaft 55 has been attained. On further movement of pedal 52, spring 70 will be tensed as sleeve 68 slides on link 63, the arrangement allowing the pedal necessary additional movement to apply the brake while maintaining signal shaft 37 in initial display position.

In the modified form of control box mechanism shown in Figs. 14, 15, 16, 19 and 21, we provide housing 73, having journalled therein the signal shaft 37, on which is mounted cam 74, adapted to engage with spring 75, which has one end 76 fixed to abutment 77, and the opposite end 78 pierced for guide pin 79, and slidble on abutment 77. Leaf spring 75 engages with cam section 80 for stop signal position, with cam section 81 for left turn signal position, and with cam section 82, for right turn signal position.

From the foregoing description and drawings, it may be seen that we have provided semaphore signal apparatus, including a signal arm, mechanism whereby the arm may be manually actuated to a plurality of display positions, and mechanism whereby the arm may be automatically actuated to initial display position upon application of an automobile brake pedal to indicate a stop or slow signal; the manually actuated mechanism being operable independently relative to the automatic mechanism, and both mechanisms having actuating springs and suitable cams whereby the signal arm is returned, when released, to normal non-display position within its protective housing.

It is our intention to provide signal apparatus that is adaptable for application to many automobiles, and to provide positive and efficient mechanism therein, and we have therefore provided a plurality of actuating springs, levers, and links in co-operative connection with one another, whereby the device may be installed on the several automobiles, without alteration or modification of the many mechanical parts.

In use, the operator will actuate handle 41, through an arc of forty-five degrees to place the semaphore arm in its initial display position for a stop or slow signal; through an arc of ninety degrees to place the semaphore in display position for left turn signal, and through an arc of one hundred and thirty-five degrees for a right turn signal. On actuating the brake pedal the semaphore arm will be actuated to its initial display position, and will return to non-display position, on release of the pedal; being actuated by the cooperative springs to initial non-display position. The illuminating feature is set forth in another patent application.

We claim:

1. In signal apparatus, a signal housing, a semaphore arm normally within the housing in non-display position, and adapted to swing outwardly to visual display positions, a shaft for actuating the semaphore arm including a square section, an actuating section, and a flexible section between the square section and actuating section, a cam mounted on the actuating section, a control box enclosing the actuating shaft section and cam thereon, a pawl within the control box and in engagement with the cam, a spring serving to maintain the pawl in operative engagement, and a handle for actuating said actuating shaft.

2. In signal apparatus, a signal housing, a semaphore arm normally within the housing and adapted to swing outwardly to display positions, a shaft for actuating the semaphore arm including a square section on which the arm is mounted, a flexible section, and an actuating section, a cam mounted on the actuating section, a control box apart

from the signal housing and enclosing the actuating section with the cam mounted thereon, a pawl within the control box and in engagement with said cam, a spring serving to maintain the pawl in constant engagement with the cam, the cam having a series of broad grooves in which the pawl engages, a lever mounted on the actuating shaft and independently rotatable thereon, a lug on the cam whereby the cam is actuated on initial movement of said lever, a handle for manually actuating the actuating shaft, and mechanism whereby the said lever may be actuated by movement of a brake pedal.

3. In signal apparatus, a housing, a semaphore arm disposed within the housing and adapted to swing outwardly therefrom to its display positions, a shaft for actuating the arm, means within the semaphore arm for illuminating the same, a control box adjacent to the signal housing, means within the control box for determining the display positions and limiting the movement of the semaphore arm, including a lever independently rotatable on the actuating shaft, an actuating cam on the shaft, a lug on the cam in engagement with said lever, and mechanism arranged whereby the actuating shaft may be actuated by movement of a brake pedal.

4. In signal apparatus, the combination with a housing, a semaphore arm disposed therein and operable to visual display positions, and an actuating shaft for the semaphore arm, of a cam on the actuating shaft, a lever independently rotatable on the actuating shaft and in engagement with the cam thereon, a wire link member having pivotal connection with the rotatable lever, a bracket adapted to be mounted on a steering wheel column, a rock shaft journaled in the bracket, the wire link member being operatively connected to one end of the rock lever, a rotatable stud journaled in the opposite end of the rock lever, a reciprocating link having one end fixed to the rotatable stud, a collar fixed thereto, a sleeve slidable thereon, an oscillatable lever having a pivotal connection with the slidable sleeve and disposed in the path of a foot pedal, and a bearing member to which the oscillatable lever is operatively secured.

5. In signal apparatus, the combination with a housing, a semaphore disposed therein and operable to visual display positions, an actuating shaft for the semaphore arm, and an independently rotatable lever mounted on the actuating shaft, and operative when moved in one direction to actuate the actuating shaft, of a wire link member having pivotal connection with the rotatable lever, a supporting bracket, a rock shaft journaled in the supporting bracket and having integral angularly disposed arms, the wire link member being operatively connected to one arm, a rotatable stud journaled in the opposite arm, a bearing member secured to a fixed

support, an oscillatable lever having pivotal connection with the bearing member, a reciprocating link having one end fixed to the rotatable stud and its opposite end terminating in a stop member, a sleeve slidable on the reciprocating link and having pivotal connection with the oscillatable lever, a collar secured to the reciprocating link, a spring connected to the collar and to the slidable sleeve, and means for limiting the movement of the independently rotatable lever on the actuating shaft whereby movement of the rock lever and links connected thereto are correspondingly limited; the oscillatable lever being disposed in the path of a vehicle foot pedal.

6. In signal apparatus, the combination with a shaft arranged for actuating a signal arm, a control box in which the actuating shaft is journaled, and a handle for manually actuating the said shaft, of a cam fixed to the actuating shaft, a lug integral with and projecting from the cam, a rotatable lever operatively mounted on the actuating shaft and normally in engagement with the projecting lug, a detent pawl in engagement with the cam, a spring serving to actuate the detent pawl, stop pins arranged to limit the movement of the rotatable lever, a bracket adapted to be mounted on a steering wheel column, a rock shaft journaled in the bracket and having integral and angularly extending arms, a wire link member operatively connected to the independently rotatable lever within the control box and to one arm of the rock lever, a collar mounted on the rock lever, a spring connected to the collar on the rock lever and to the supporting bracket whereby to actuate the rotatable lever within the control box to neutral position, a rotatable stud mounted in the opposite arm of the rock lever, a reciprocating link fixed to the rotatable stud, a bearing member adapted to be mounted on the automobile flooring, an oscillatable lever operatively connected to the said bearing member, and disposed in the path of the automobile brake pedal, a sleeve slidable on the reciprocating link, and having pivotal connection with the oscillatable lever, a collar fixed to the reciprocating link, and a spring mounted on the reciprocating link and connected to the fixed collar thereon and connected to the slidable sleeve, whereby the mechanism is actuated to actuate the signal arm shaft on the initial part of movement of the brake pedal.

7. In signal apparatus, the combination with a shaft for actuating a signal arm, a cam on the shaft, a lug on the cam, a rotatable lever operatively mounted on the shaft and engaging with the lug to actuate the signal actuating shaft, and means for limiting the movement of the independently rotatable lever, of a supporting bracket apart from the actuating shaft and lever thereon, a rock

shaft journalled in the supporting bracket and having opposed lever arms extending angularly from the rock shaft, a wire link member operatively connected to the independently rotatable lever on the signal actuating shaft and operatively connected to an arm of the rock lever, a collar on the rock lever, a spring connected to the collar and to the supporting bracket and tending to urge the independently rotatable lever in one direction of movement, a rotatable stud journalled in the opposite arm of the rock lever, a reciprocating link member fixed to the rotatable stud, a supporting member adapted to be fixed to an automobile flooring adjacent to the brake pedal thereof, an oscillatable lever operatively connected to said supporting member, and disposed in the path of the brake pedal, a sleeve slidable on the reciprocating link member, a collar fixed to the reciprocating link member, a spring connected to the collar and sliding sleeve on the reciprocating link member, whereby the mechanism is actuated to actuate the signal arm shaft on initial movement of the brake pedal, and a stop forming the end of the reciprocating link member and engaging with the automobile flooring to limit the movement of said link member, the spring thereon being tensed as the reciprocating link approaches the limit of its movement.

In testimony whereof, we hereunto affix our signatures.

H. YAMAKI.
